UNITED STATES PATENT OFFICE.

PHILIPP GOLDSCHMIDT, OF PATERSON, NEW JERSEY.

ELECTRIC STOP-MOTION FOR WARPING-MACHINES.

SPECIFICATION forming part of Letters Patent No. 443,674, dated December 30, 1890.

Application filed January 11, 1890. Serial No. 336,654. (No model.)

To all whom it may concern:

Be it known that I, PHILIPP GOLDSCHMIDT, of Paterson, in the county of Passaic and State of New Jersey, have invented a certain new and useful Improvement in Electric Stop-Motions for Warping-Machines, of which the following is a specification.

My improvement relates to stop-motions employed in machines for warping, and is particularly adapted to machines for the warping of silk.

I will describe my improvement in detail, and then point out the novel features in claims.

15 In the accompanying drawings, Figure 1 is a side elevation of a portion of a warping-machine and a stop-motion embodying my improvement. Fig. 2 is a plan or top view of the same. Fig. 3 is a view on an enlarged 20 scale of a portion of the stop-motion, the said view being partly in section. Fig. 4 is a detail partly in section and partly broken away, and looking in the direction of the arrow, Fig. 3.

25 Similar letters of reference designate corresponding parts in all the figures.

In carrying out my improvement I take threads from a creel, and after passing them through a reed, deliver them onto a drum.

30 After leaving the drum they pass to a spool. In passing over the drum they cause the rotation of the latter by friction. The drum drives indicator mechanism by which the 35 number of yards of thread passing to the spool is measured. In conjunction with the indicator mechanism I employ a stop-motion, which stop-motion is operated, when a sufficient number of yards has been passed to the spool, to stop the machine. I further 40 cause the operation of the same stop-motion electrically to cause the stopping of the machine upon the breaking of a thread passing from the creel.

I will first describe the passage of the thread 45 to and over the drum and the operation of the indicator mechanism.

Threads A are delivered from a creel A'. (Shown as in the main of ordinary construction.) Spools w are arranged upon spindles 50 w'. The threads pass upwardly and over a rod w² near the upper end of the creel. After

leaving the rod w² they pass through a reed w³, and from thence separately through faller-wires w⁴. The faller-wires w⁴ are shown as pivoted near their lower ends upon a metallic bar 55 w⁵, secured upon but insulated from the creel. They are provided with curls or eyes w⁶, through which the threads extend. Beyond the curls or eyes w⁶ they have straight portions w⁷. The threads in passing through 60 the curls or eyes w⁶ operate to maintain the faller-wires in an elevated position. Should one of the threads break, the faller-wire through which it passes will fall and contact with a metallic contact-piece w⁸, extending 65 widthwise of the creel and mounted upon but insulated from arms w⁹, extending from the creel. When the faller-wire falls, it operates as a circuit-closer to close an electric circuit and cause the operation of a stop-motion to 70 stop the machine in a manner to be presently described. The thread after leaving the faller-wire passes over glass rods a. Alternate threads pass over and under said rods, so as to cross each other in a well-known manner. 75 From the rods a the threads pass beneath a rod a', and from thence onto and over the drum B. The drum B is journaled, as at a², in brackets B', extending upwardly from the frame B² of the machine. The threads in 80 their passage over the drum impart rotary motion to the latter by friction. Upon the shaft of the drum is mounted a worm b, which worm meshes with a worm-wheel b', mounted on a vertically-extending shaft b², journaled 85 in the frame B², and also in a bracket B³, extending upwardly from said frame. The upper end portion of the shaft b² carries a worm b³, which worm meshes with a worm-wheel b⁴, mounted upon a shaft b⁵, journaled in the 90 bracket B³.

C designates an indicator-dial. This dial is scored upon its face and near its periphery to indicate the number of yards of thread which it is desired to wind upon a spool. This 95 dial is loosely mounted on the shaft b⁵.

C' designates a hand-wheel, which hand-wheel is provided with a hub c, secured on the dial C. The hand-wheel and hub also loosely surround the shaft b⁵. Although I 100 have stated that the dial, hand-wheel, and hub loosely surround said shaft, I wish it to be

understood that they are held in frictional contact with said shaft, so that when the shaft rotates they will rotate with it.

Assuming that it is desired to place three hundred and sixty yards upon the spool, the wheel C' is operated by hand, and the indicator-dial is thereby rotated from zero progressively toward the number "360" and until said number is opposite a given point. In this instance such point is a toe d on a lever d', which lever is fulcrumed upon a bracket d'', extending upwardly from the bracket B''. The toe d occupies a position vertically and directly over the dial. At the zero-point on the dial is a notch d''. The dial having been set as described and the machine put in operation, the dial rotates toward the zero-point, and when it reaches the zero-point the toe d will drop into the notch d'', which will result in operating a stop-motion for the machine, to be presently described.

The driving mechanism between the drum B and the indicator-dial is so timed that the rotation of the drum will deliver only the desired number of yards of warp onto the spool that is provided for in the adjustment of the dial.

G designates a main driving-shaft journaled in suitable bearings upon the main frame. This shaft derives motion from a fast pulley g' on the main shaft. Said main shaft is also provided with a loose pulley g'.

I have shown a stop-motion for stopping the machine when the proper quantity of warp has been received upon the spool. When the toe d upon the lever d' drops into the notch at the zero-point on the dial C, a rod H, suspended from a horizontally-extending rod H', connected with the lever d', also falls, such fall being occasioned by gravity. The rod H slides vertically in suitable bearings in an upright I', and is provided with a horizontally-extending tooth or projection i. (Shown more clearly in Fig. 4.) The upright I' is provided with two transversely-extending apertures i' i''.

Referring more particularly to Figs. 3 and 4, J designates a rod adapted to move to and fro through the aperture i'' in the upright I'. Longitudinal movement is imparted to the rod J from an eccentric J' on the shaft G by means of an eccentric-rod J'', one end of which connects with one arm of a bell-crank lever J'', the other arm of which has connected to it the rod J. The bell-crank lever J'' is fulcrumed upon the frame B''. The other end of the rod J is connected by means of a cross-head or yoke J' to a rod J'', which rod is adapted to be moved to and fro through the opening i' in the upright I' and also through a suitable opening in a bracket j'', extending upwardly from the frame B''. The cross-head or yoke J' has a loose connection with the rod J'', so that it may under certain circumstances slide upon said rod. It is caused, however, to impart longitudinal movement to the rod J'' by a spring J'', which surrounds the

rod J'' and is interposed between the cross-head or yoke J' and a collar j upon the rod J''. The resistance of this spring is such that when the passage of the rod J'' is unobstructed through the aperture i' in the upright I' the cross-head or yoke J' will cause longitudinal movement of the rod J''. When the rod H falls, the tooth i thereon will be brought opposite the aperture i'', and thus prevent longitudinal movement of the rod J''. A continued reciprocation of the rod J'' is, however, permitted, owing to the spring J''.

Pivoted upon the rod J'' is a lever J', which lever has a loose connection near its lower end (as shown being held between pins) with the cross-head or yoke J'. When the rods J J'' are reciprocating in unison, this lever moves with the rods; but when the movement of the rod J'' has been stopped the lever J' is by the movement of the rod J rocked upon its fulcrum. It then operates to raise a trip L, provided with a tooth l, engaging a projection l' upon a lever L'. The lever L' is fulcrumed near the base of the frame B'' and has connected to it one end of a belt-shifter rod L'', which belt-shifter rod carries at its other end a belt-shifter L'', by which the belt may be shifted from the fast to the loose pulley, or vice versa.

In the operation just described the belt is shifted to the loose pulley, and the machine is therefore instantly stopped. The movement of the lever in one direction or in the direction to stop the machine is facilitated by a spring L', connected thereto and to the frame B''. The machine is again started, of course, by rotating the dial C sufficiently to raise the toe d out of the notch d'' and again operating the lever L' to engage it with the trip L.

Secured to the lower end of the rod H, but insulated therefrom, is an armature P. This armature is adapted to be attracted by an electro-magnet P'. One pole of the magnet is in circuit with a battery P''. From the other pole a wire n extends to the metallic cross-bar w'', upon which the faller-wires w' are pivoted. A wire n' extends from the metallic cross-bar w'' to the other pole of the battery P''. When a thread breaks and the faller-wire drops upon the metallic cross-bar w'', circuit will be closed on the electro-magnet P' and the armature P will be attracted. This will cause a sidewise swinging movement of the rod H, which will cause said rod to extend across the opening i' in the upright I', thus closing said opening and preventing longitudinal movement of the rod J'', whereupon a similar action will occur to effect the stoppage of the machine to that previously described. When the faller-wire which closed circuit has been again raised to break circuit, the armature P will swing backwardly from the electro-magnet P', thus again uncovering the opening i' and admitting of the operation of the machine.

I have shown at intervals upon the face of the dial pins or projections o. These of course

rotate with the dial and are adapted to come in contact with a circuit-closer O, which may be of any suitable kind, mounted upon the main frame. From this circuit-closer a wire 5 o' extends to the battery, and another wire o² extends from the circuit-closer to a bell-signal R, of ordinary construction. From the bell-signal R a wire o³ extends to the other pole of the battery. When one of the pins o comes 10 in contact with the circuit-closer O to close circuit, an audible signal will be given, which will indicate the number of yards already passed over the drum. Of course I may use any desired number of the pins o. 15 I have not illustrated the spindle mechanism nor the means for operating the same, as the same does not broadly constitute part of my invention, and by their omission I have been enabled to give larger and clearer views. 20 It will be seen that by my improvement I am enabled to employ a single stop-motion controlled both by the rotation of the dial and also by the breaking of a thread from the creel, this stop-motion being operated through 25 the movement of a single rod.

What I claim as my invention, and desire to secure by Letters Patent, is—

1. In a warping or similar machine, the combination, with a single stop-motion, of a dial

for indicating the number of yards of threads being wound, a rod moved in one direction when the dial has rotated to a certain point to cause the operation of the stop-motion, a creel provided with faller-wires through which the threads being wound pass, contact-pieces 35 through which circuit is closed by any of said faller-wires upon the breaking of a thread passing through the same, a battery, an electric circuit, and an electro-magnet operating when circuit is closed by the falling of a faller-wire to move said rod to operate the said stop-motion, substantially as specified. 40

2. In a warping-machine, the combination, with a rotary dial provided upon its face with pins or projections and a creel provided with 45 faller-wires through which the threads being wound pass, of circuit-closers upon which circuit may be closed by said pins and faller-wires, a single stop-motion under the control of an electric circuit closed by either the pins on the dial or faller-wires, a battery, an electric circuit, and a signal, substantially as set forth.

PHILIPP GOLDSCHMIDT.
